UNITED STATES PATENT OFFICE.

DANIEL EASTMAN TRUE, OF LEOMINSTER, MASSACHUSETTS.

PAIL FOR COMMODES.

SPECIFICATION forming part of Letters Patent No. 323,469, dated August 4, 1885.

Application filed June 22, 1885. (No model.)

To all whom it may concern:

Be it known that I, DANIEL EASTMAN TRUE, of Leominster, in the county of Worcester, of the Commonwealth of Massachusetts, have invented a new and useful Improvement in Pails for Commodes, &c.; and I do hereby declare the same to be described in the following specification, and represented in the accompanying drawings, of which—

10 Figure 1 is a side elevation, and Fig. 2 a transverse and vertical section, of a commode-pail of my invention, the nature of which is defined in the claim hereinafter presented.

15 The body A of the said pail is cylindrical, and is provided with a mouth-piece, B, which has the shape of the frustum of a cone. The cover C, to fit on the upper part of such mouth-piece, is provided with an elastic ring or band, D, that, fixed to and encompassing the outer 20 periphery of such cover, extends downward and encircles and closely laps on the mouth-piece, so as to virtually hermetically seal the joint of the cover and mouth-piece to prevent the escape from the pail of any disagreeable odor arising from fecal matter or urine when in the pail. The cover has a handle, a, and there is also to the body of the pail a bail, b, for lifting the pail out of a commode and transferring

such pail to any point at a distance therefrom as occasion may require. The sealing ring or band D, I usually make of vulcanized india-rubber.

In practice I have found such a commode-pail of great utility and very effective in keeping within it any disagreeable odor or offensive gas arising from any fecal or other matter within the pail. The elastic band does not prevent the cover from being readily removed from or applied to the mouth-piece; but when the cover is forced downward over the mouth-piece the band becomes expanded by the latter and fits closely and air-tight thereto.

I claim—

The combination of the vessel or body A, provided with the conical or tapering mouth-piece B, with the cover C therefor having the elastic band extending down from its periphery and encompassing and fitting by its inherent elasticity tightly upon the outer surface of the said mouth-piece, all being substantially and for the purpose as set forth.

DANIEL EASTMAN TRUE.
